His Attorney.

UNITED STATES PATENT OFFICE.

EUGENE PONS, OF SCHENECTADY, NEW YORK, ASSIGNOR TO GENERAL ELECTRIC COMPANY, A CORPORATION OF NEW YORK.

MAGNETIC SWITCH.

Application filed February 16, 1922. Serial No. 537,106.

To all whom it may concern:

Be it known that I, EUGENE PONS, a citizen of the United States, residing at Schenectady, in the county of Schenectady, 5 State of New York, have invented certain new and useful Improvements in Magnetic Switches, of which the following is a specification.

My invention relates to improvements in 10 magnetic switches and particularly to an improved arrangement for operating a circuit controlling switch member quickly toward and from the closed circuit position in synchronism with the operation of a comparatively slow moving controlling member.

One of the objects of the invention is to 15 provide a switch of the character indicated which shall be simple in construction and reliable in operation, and one which can be 20 cheaply manufactured.

In carrying my invention into effect in 25 one form, I provide a pair of relatively movable substantially similar magnets disposed with respect to each other so that the poles of opposite polarity are adjacent each other. A magnetic movable member which controls 30 a switch member is biased away from one of the magnets and is adapted to be magnetically attracted and held by that magnet. When the magnetic movable member takes 35 the form of a soft iron armature, this armature is adapted to bridge the poles of one of the magnets and be thus magnetically held against its bias when the other magnet 40 is at such a position with respect to the first magnet that the magnets have no effect on each other. When the poles of the two magnets are brought into close proximity to 45 each other, the armature is quickly released, and when the magnets are again displaced the armature is again attracted against its bias. The relative movement between the magnets may be quite slow, but the make and break of the circuit controlled by the 50 switch member carried by the armature is quick and positive.

Furthermore, if the circuit controlling contacts controlled by the magnetic movable member are located between the poles of the magnets, the magnetic flux of the magnets is effective in disrupting the arcs formed between the contacts.

For a better understanding of my invention, reference is had to the accompanying 55 drawing wherein I have illustrated an em-

bodiment of the invention for the purpose of explaining the principles thereof. Referring to the drawing, Fig. 1 shows a plan view of a magnetically controlled switch which is opened and closed quickly in response to the comparatively slow movement of the pressure responsive device; Fig. 2 is a cross-sectional view taken on the cross-section line indicated in Fig. 1 with the switch in its normal open or biased position; Fig. 60 65 3 is a view similar to Fig. 2 with the parts in their relative positions when the switch is closed; and Fig. 4 is a detail showing the relative positions of the two magnets when the switch is in the closed position.

Referring to the drawings, the switch comprises a switch member 10 which is resiliently connected to a base 11 of insulating material by means of the support 12 which biases the movable contacts 13 and 14 of the 70 75 switch to their respective open positions. This switch member 10 is connected to a magnetic movable member or armature 15 which is adapted to bridge the poles of the horseshoe type permanent magnet 16. The 80 armature 15 is preferably of soft iron having a low permeability. The horseshoe type permanent magnet 17 is substantially similar to the permanent magnet 16, and these two magnets are disposed with respect to each other so that poles of opposite polarity are adjacent each other. The two magnets are capable of having a relative movement with respect to each other by reason of the fact that permanent magnet 17 is secured to 85 the lever 18 which is pivotally mounted at 90 95 19. A spring 20, which cooperates with the pivotal support 19 and the lever 18, is provided for biasing the lever and the magnet to any predetermined desired position. The pressure responsive device 21 is provided with a piston 22 which is pivotally connected to the lever 18 so that this lever is reciprocated back and forth on its pivot 19 in response to the variations of pressure in the 100 pressure responsive device 21. It will be apparent that while I have shown an arrangement in which the relative movement between the two magnets 16 and 17 is responsive to variations of fluid pressure, this 105 relative movement may be in response to any other predetermined condition, as, for example, in response to changes of temperature or in accordance with the movement of any movable device.

As thus constructed and arranged, the operation of my invention is briefly as follows:—When the lever 18 is in the position shown in Fig. 1, the poles of the permanent magnet 17 will be in contact with the poles of the permanent magnet 16, so that the magnetic fluxes of the two magnets supplement each other, and by reason of the fact that the flux of the magnet 16 has a path of lower reluctance through the magnet 17 than through the armature 15, this armature will not be attracted, and the switch controlled by the armature will be in the open position. When the pressure changes so that the lever 18 is moved clockwise to carry the magnet 17 away from the magnet 16 as indicated in Figs. 3 and 4, the magnetic flux of the magnet 16 will have a path of lower reluctance through the armature 15, and this armature will be attracted so as to bridge the poles of the magnet 16. The contacts 13 and 14 of the switch are thereby brought into engagement with the stationary contacts 23 and 24, and a circuit is thus completed through the switch member 10. The armature 15 will be attracted by the magnet 16 so as to move quickly to the attracted position, and when the magnet 17 is again brought into engagement with the magnet 16, the armature is quickly released. The make and break of the electric circuit controlled by the armature 15 is thereby quick and positive even though the movement of the lever 18 in response to the changes of pressure may be comparatively slow. It will also be observed that the magnetic flux set up by the two magnets will have an effect in magnetically disrupting the arcs formed between the switch contacts, since these contacts are disposed within the magnetic field set up by the magnets.

The switch is simple in construction and reliable in operation, and it can be cheaply manufactured because of the fact that it has a comparatively few simple parts.

In accordance with the provisions of the patent statutes, I have described the principle of operation of my invention, together with the apparatus which I now consider to represent the best embodiment thereof,

but I desire to have it understood that the apparatus shown is only illustrative and that the invention may be carried out by other means.

What I claim as new and desire to secure by Letters Patent of the United States, is:—

1. A magnetically controlled switch comprising a magnet, a magnetic movable member therefor adapted to be magnetically attracted and held by the said magnet, a switch member controlled by the said magnetic member, a second magnet substantially similar to the first magnet and disposed with respect to the first magnet so that poles of opposite polarity are adjacent each other, and means for imparting relative movement to the said magnets to control the said magnetic member and switch member.

2. A magnetically operated switch comprising a permanent magnet, an armature therefor adapted to bridge the poles of said magnet, a switch member carried by the said armature, a second permanent magnet substantially similar to the first magnet and disposed with respect to the first magnet so that poles of opposite polarity are adjacent each other, and means for imparting relative movement to the said magnets to control the said armature and switch member.

3. A magnetically operated switch comprising a permanent magnet, an armature therefor adapted to bridge the poles of said magnet and biased away from the attracted position, a switch contact member carried by the said armature, a second permanent magnet substantially similar to the first magnet and disposed with respect to the first magnet so that poles of opposite polarity are adjacent each other, and means for moving the second magnet out of contacting relation with the poles of the first magnet to permit the said armature to move to the attracted position and for moving the second magnet into contacting relation with the poles of the first magnet to permit the said armature to release in accordance with its bias.

In witness whereof, I have hereunto set my hand this 15th day of February, 1922.

EUGENE PONS.
